UNITED STATES PATENT OFFICE.

HARRY E. DUNHAM, OF SAGINAW, MICHIGAN, ASSIGNOR OF ONE-HALF TO
AARON T. BLISS, OF SAME PLACE.

DINNER-PAIL COVER.

SPECIFICATION forming part of Letters Patent No. 519,809, dated May 15, 1894.

Application filed February 6, 1894. Serial No. 499,271. (No model.)

To all whom it may concern:

Be it known that I, HARRY E. DUNHAM, a citizen of the United States, residing at Saginaw, in the county of Saginaw and State of Michigan, have invented certain new and useful Improvements in Dinner-Pail Covers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention is a cover for a dinner pail, and consists in the peculiar construction and adaptation and combination shown and described and claimed.

Heretofore it has been common to place in 20 a dinner pail a lamp or heater for the purpose of warming the contents when desired or for keeping the same from freezing when exposed to cold weather. Many different pails have been constructed showing the lamp 25 or heater arranged therein in as many different positions and forms, taking up more or less of the space within the pail, making it necessary to make the pail larger or receive less contents. With my invention all the 30 space within the pail is saved and at the same time a heater is provided by which the user can warm his tea or coffee and viands before eating. This heater I provide in the top of the cover for the pail.

35 Figure I, is a side view of the cover showing the top of the heater. Fig. II, is a side perspective of the same. Fig. III, is a section through the pail cover showing the heating chamber. Fig. IV, is a side perspective 40 showing the cup arranged and fitting over the top of the heater.

In the drawings, A, is the pail cover having a raised top B, upon which are arranged cup holders D, D.

C, is a partition placed within the pail cover 45 at such a point that when the cover is upon the pail it rests upon the top of the pail and thereby provides a chamber in the upper part of the cover.

L, are tubes extending through the top of 50 the cover provided with wicks, and in the chamber of the cover may be placed alcohol or oil into which the wicks in the tubes L, extend, thereby forming a lamp. These tubes L, are shorter than the cup holders D, D, and 55 upon these cup holders the dinner pail or cup or other vessel may be set for warming when the lamp is lighted.

It is obvious that any other form of lamp could be used without departing from the 50 principle of my invention.

Having, therefore, described my invention, what I claim as new, and desire to secure by Letters Patent, is—

1. In a dinner pail cover the combination 65 with the cover of the oil reservoir of a lamp in the upper half of the cover and integral therewith, tubes extending upward therefrom, lamp wicks in the said tubes extending into the oil reservoir, and means for supporting a 70 vessel above the lamp thus formed, substantially as described.

2. In a dinner pail cover, the combination 75 with the cover, and cup holders upon the top of the cover, of a lamp formed within the cover having the burner within the cup holders, and the cup adapted to be held in place upon the cover by the cup holders and protect the lamp burner, substantially as described. 80

In testimony whereof I affix my signature in presence of two witnesses.

HARRY E. DUNHAM.

Witnesses:

A. H. SWARTHOUT,
FANNIE ROBBINS.
